UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING ORE AND THE LIKE.

Application filed April 27, 1921. Serial No. 484,942.

This invention relates to improvements in apparatus for handling ore and the like and has for its principal object to provide a simple and durable conveying apparatus for 5 transporting loose material from one place to another as for instance in a mine.

In a prior application, Serial No. 382,696, filed May 20, 1920, now Patent 1,462,688, July 24, 1923, I have disclosed an apparatus 10 of the class above described comprising a scraper and a movable frame adapted to form a support about which said scraper is guided. In the present application, I utilize the same general principles of construction 15 and operation as therein described, but provide certain improvements in the construction of the scraper and draft means used therewith, as will hereinafter more fully appear.

20 My invention may best be understood by reference to the accompanying drawings in which Figure 1 is a top plan view. Figure 2 is a longitudinal cross-section of the scraper. Figure 3 is a side view of the apparatus shown in Figure 1 illustrating its use in a mine.

In the embodiment of my invention illustrated, the apparatus is adapted for use in mining operations in which loose material 30 is to be transported from the working face, or place from which the material is being mined, to a place where it may be loaded on mine cars. The loading apparatus comprises a scraper 1 adapted to be moved on the mine bottom by means of suitable draft cables about a guiding frame 2 adapted to be fixed on the mine bottom in position to form a bearing for one side of the scraper as the latter is advanced into the loose material.

40 In order to illustrate the present invention I have shown a bearing frame similar to that shown and described in the prior application mentioned. This frame is provided with a curved forward end 2^a and a pair of rearwardly extending beams 4, 4 having a slot 5 therebetween. The forward end 2^a is preferably provided with a plurality of rollers 3, 3 and forms a guiding and bearing 45 surface for the scraper 1. The frame 2 is adapted to be held in place by means of a suitable guiding device such as a pair of jacks 6, 6^a of the usual type adapted to be inserted in the slot 5. The jacks 6, 6^a are

spaced apart so as to restrain movement of the frame in a lateral direction but allows 55 movement thereof in a longitudinal direction. Movement of the frame is preferably accomplished by means of a draft device which may comprise a flexible cable 7 adapted to be fixed at the forward end by some 60 suitable anchor as for instance the jack 6^a and operated by means of a ratchet device comprising a drum 8, and an operating lever 8^a. It will be understood, however, that any equivalent means may be provided for moving the guiding frame forward with respect to the fixed guiding jacks 6 and 6^a as the loading operation proceeds.

65 The scraper 1 is operated by means of suitable draft means, comprising a drag rope 70 9, and a tail rope 10, each connected with a suitable winding engine (not shown) located at a distance from the frame 2. The scraper may be of any suitable shape, but for the purpose of illustration I have shown 75 herewith a preferred form of scraper having a body portion 11 shaped in accordance with the scraper body shown and described in my co-pending application, Serial #460,- 80 865, now Patent 1,464,522, Aug. 14, 1923.

85 The present invention relates particularly to novel means of attaching the head rope 9 to the scraper. An arm 12 is attached to a suitable transverse member 13 on the scraper 1. Said member is preferably attached to 90 the scraper at or near the upper margin thereof so as not to interfere with the loading or unloading of the scraper. The arm 12 is pivoted on a pin 16, to swing in a horizontal plane.

95 An auxiliary brace member may also be provided if desired comprising a second cross member 14 mounted forward of cross member 13 and above the arm 12, having a rearwardly projecting brace 15 attached to 100 the pivot pin 16. The forward end 17 of the pivoted arm 12 is bent downward substantially at right angles as shown and is provided with a series of holes 18, 18, to any one of which one end of dragline 9 may be suitably attached. By means of this arrangement the height of the chain may be changed with respect to the scraper as desired.

105 The drag line 9 comprises a length of chain 19 connected to the scraper, and having length sufficient to extend about the for-

ward or bearing end 2^a of the guiding frame 2 when the scraper is in position to be moved forwardly about said frame. The forward end of the chain is attached to a flexible cable 20.

The use and operation of the apparatus above described is as follows:—The guiding frame is positioned adjacent the pile of material to be transferred, with the draft ropes 10 connected with the winding engine, suitably located to move the scraper toward a loading chute, or the like. The scraper is pulled rearward by the tail rope 10 about the guiding frame until the open end of the scraper 15 faces the pile of loose material. In this position arm 12 will be swung laterally to one side and adjacent to the front face of the guiding frame as shown in Figure 1 thereof, leaving the front end of the scraper unobstructed for gathering the material. The scraper is loaded as it moves about the frame with one side thereof in lateral engagement with the frame. After the scraper leaves the frame the pivoted arm 12 assumes a longitudinal position with respect to the scraper so that the latter is advanced forwardly toward the loading chute. After the scraper is unloaded it is returned to its initial position by tail rope 10 and it is ready to collect 20 another load. As the material within reach of the scraper is collected the frame is moved forward by means of the draft device 7 and the ratchet 8 to advance the scraper into the pile. The head frame 2 may be moved into 25 various positions as desired by placing the guiding jacks 6 and 6^a as desired.

The length of chain 19 which constitutes a portion of the head rope is provided because I find in practice that a flexible cable of the usual type is liable to "whip" about and leap off the guiding frame. This is eliminated by the use of the short chain length as shown.

I do not claim the specific form of scraper 30 shown in Figures 1 and 2 as this is claimed in my co-pending application bearing Serial Number 460,865, filed April 13th, 1921.

Having described my invention what I

claim as new and desire to cover by Letters Patent, is:—

1. In a conveying apparatus, the combination of a frame having a curved bearing portion, a scraper adapted to have lateral engagement with said frame, draft means for said scraper, and means connecting said draft means and said scraper comprising a laterally swinging arm connected with the latter intermediate its sides. 55

2. In a conveying apparatus, the combination of a frame having a curved bearing portion, a scraper adapted to have lateral engagement with said frame, draft means for said scraper, and means connecting said draft means and said scraper comprising a laterally swinging arm connected with the latter intermediate its sides, and forwardly of the center of said scraper. 60

3. In a conveying apparatus, the combination of a frame having a curved bearing portion, a scraper adapted to have lateral engagement with said frame, draft means for said scraper, and means connecting said draft means and said scraper comprising a laterally swinging arm connected with the latter intermediate its sides, and adjacent 70 the upper margin thereof, said arm having a downwardly extending portion at its forward end having connection with said draft means.

4. In a conveying apparatus, the combination of a frame having a curved bearing portion, a scraper adapted to have lateral engagement with said frame, draft means for said scraper, and means connecting said draft means and said scraper comprising a 85 laterally swinging arm connected with the latter intermediate its sides, and adjacent the upper margin thereof, said arm having a downwardly extending portion at its forward end, and means affording connection 90 with said draft means at a plurality of points along said downwardly extending portion.

Signed at Chicago, Illinois, this twenty-fifth day of April, 1921.

CHARLES E. DAVIS.
